UNITED STATES PATENT OFFICE.

HENRY HERBERT LUSCOMB, OF BOSTON, MASSACHUSETTS.

HANGER FOR ELECTRIC WIRES.

SPECIFICATION forming part of Letters Patent No. 472,220, dated April 5, 1892.

Application filed July 20, 1891. Serial No. 400,019. (No model.)

To all whom it may concern:

Be it known that I, HENRY HERBERT LUSCOMB, a citizen of the United States, residing at Boston, in the county of Suffolk and State 5 of Massachusetts, have invented certain new and useful Improvements in Hangers or Supports for Overhead Electrical Conductors, of which the following is a specification, reference being had therein to the accompanying 10 drawings.

My invention has for its object to produce an improved hanger or support for overhead electrical conductors for electric railways; and it relates to hangers or supports which 15 are intended particularly for that portion of the conductor which passes around a curve and which are commonly called "pull-offs." The trolley which makes contact with the conductor has a grooved periphery, as is well 20 known, and the conductor must be so supported or mounted as to permit the trolley to pass along underneath it without interference with the overhead construction. To this end the hanger is usually arched or hook-shaped; 25 but inasmuch as the strain on it is oftentimes very great the hook now in use is apt to straighten or bend or break. Furthermore, in pull-offs as ordinarily constructed single insulation only is obtained, and no pull-off 30 known to me is constructed embracing the feature of double insulation, which feature is desirable for reasons well known to those skilled in the art. By constructing the device in accordance with my invention I am 35 enabled to produce a hanger which is not liable to straighten or bend or break, and I am also enabled to employ the feature of double insulation when that is desired.

I have shown in the accompanying drawings 40 the best forms of my invention now known to me and will now proceed to describe the same with reference to the said drawings, after which I will point out in the claims the novel features thereof.

In the drawings, Figure 1 is a side elevation 45 of the preferred form of my improved hanger or support. Fig. 2 is a section on line 2 2, Fig. 1. Fig. 3 is a section on line 3 3, Fig. 1. Fig. 4 is a plan view of the end of the 50 shank, showing the eye by which it may be connected with the cross-wire. Fig. 5 is a

side elevation, partly in section, of a slightly modified form of my invention, showing double insulation. Fig. 6 is a section on line 6 6, Fig. 5. Fig. 7 is a plan view of the device as shown 55 in Fig. 5. Fig. 8 is a side elevation of still another modification of my device. Fig. 9 is a plan view of the modification shown in Fig. 8.

The construction of my device is simple and will be readily understood. The electrical 60 conductor is shown at A. B is an attaching ear, which may be soldered or otherwise secured to the conductor. Any well known form of ear or clip may be employed. A threaded socket is provided in the upwardly 65 extending shank of the ear or clip, into which a threaded bolt or projection c may be screwed. The threaded bolt c may be integral with the head d, or the head may be enlarged at the lower end, as shown in Figs. 1 and 2, and provided with a threaded socket, into which one 70 end of bolt c may be screwed, as shown in Fig. 2. It will be noted that the ear B has a firm bearing against the lower end of the head d, which is desirable. The head d is preferably 75 of metal and is made in the form shown in Fig. 2—that is, it is flanged or webbed throughout a portion of its length and is thus cruciform in cross-section throughout that portion, as shown in Fig. 3. The upper end of 80 the head is preferably enlarged, as shown, so that it may be the more securely embedded in or attached to the casing of non-conducting material f when it is desired to insulate this portion of the device. Any well-known 85 non-conducting material may be employed to cover and insulate the head d. The non-conducting casing when employed should preferably terminate in a skirt g, Figs. 1 and 2, in order to more effectually secure against short-circuiting by moisture. A clamp or strap h, 90 which is adapted to fit an annular groove in the non-conducting casing of the head, is adapted to be sprung onto the casing and is provided with lugs or projections, (see Fig. 3,) 95 between which is pivoted a stem or shank k. The stem is provided with an upwardly-projecting arm l, which is webbed, as shown in the cross-sectional view, Fig. 3, and turned at its upper end so that it may bear against the 100 upper part of the non-conducting casing f of the head. Where the upper end of the arm

touches the casing the casing is provided with a wear-plate $l^{\prime\prime}$, which is set therein and is preferably flush with the surface thereof. The arm or brace l acts first as a stop when the hanger is in use to prevent the head d from being pulled over and afterward as a brace to transmit the strain of the head to the stem k . The outwardly-extending or free end of the stem k may simply terminate in an eye, such as is shown in Fig. 4, by means of which the device may be attached to a cable or supporting-wire, and this end of the stem may or may not be provided with insulation. If the end be insulated, as shown in Figs. 1 and 5, the insulation at this point may be effected in any well-known manner; but I prefer to accomplish it as shown—that is, the free end of the stem is enlarged in the conical form shown and is covered with a layer of suitable non-conducting material m . A collar n of corresponding conical shape is placed around the enlarged end outside of the non-conducting material, and a cap p , having a suitable eye therein, is screwed onto the collar n , preferably covering the non-conducting material at the end of the stem k , all as clearly shown in Fig. 5. By this form of construction, which I deem the preferable form, a hanger or support is produced, such as is shown in Fig. 1. This hanger, it will be understood, has the feature of double insulation—that is, the conductor is insulated at the head d by means of the non-conducting casing f and again at the end of the stem k by means of the insulation m . It will be further understood that by means of the pivot at the heel or end of the stem k the lateral strain, which tends to pull the head out of the vertical, is distributed through the brace l to the stem k . In this way parts of less strength and size may be used than could be employed if the usual rigid hook construction were adopted. The stem k may be set at any angle with reference to the conductor A by reason of the screw connection c between the ear or clip B and the head d .

Figs. 5, 6, and 7 show a slightly-modified form of my invention, the chief modifications being the form of the metallic head d , which is a bolt without a head, having a circular cross-section, the two-part form of the clamp or holder h , which, instead of being made in a single piece and sprung onto the non-conducting casing of the head, is made in two pieces and bolted, as shown at j' , Fig. 7, and the absence of a skirt on the insulating casing of the head. The cross-sectional shape of the holder is also different, it being convex to fit an annular bulge or projection on the non-conducting material.

Still another modification of my device is shown in Figs. 8 and 9, in which only one insulation is employed and that at the free

end of the shank or stem k . When the insulation at the head of the device is omitted, 65 the lugs j are preferably integral with the head d , as shown in said figures. In the latter modification the brace or arm l rises vertically from the stem k , and the upper end of the brace passes through a slot in a laterally-projecting arm l' , secured to the top of the head d , through which the strain of the head when in use is transmitted. For greater strength I prefer to brace the arm l by an inclined brace $l^{\prime\prime}$, which is set between the stem 75 k and the upper end of the arm l .

It will be obvious that where single insulation only is desired it may be obtained either at the free end of the stem k , as shown in Fig. 8, or at the head of the device, as shown in 80 Fig. 1, and it will be also obvious that if the insulation be on the stem k it need not be placed at the free end of the stem, but may be midway thereof or at any point in said stem.

What I claim is—

1. A support or hanger having a head, a stem to one end of which the head is pivoted, and an arm serving as a stop for the head and also to transmit a part of the strain on the head when in use to adjacent parts of the stem, 90 substantially as described.

2. A support or hanger having a head provided with a casing of non-conducting material and carrying a wire-engaging device, a stem to which the said head is pivotally connected, and an arm serving as a stop for the head and also to transmit a part of the strain on the head when in use to adjacent parts of the stem, substantially as described.

3. A support or hanger having a head provided with a casing of non-conducting material and carrying a wire-engaging device, a clamp or holder, a stem to which the head is joined by pivotal connections between the clamp or holder and the stem, and an arm 105 serving as a stop for the head and also to transmit a part of the strain on the head when in use to adjacent parts of the stem, substantially as described.

4. A support or hanger having a head provided with a casing of non-conducting material and carrying a wire-engaging device, a stem to which the said head is pivotally connected, and an arm serving as a stop for the head and also to transmit a part of the strain 115 on the head when in use to adjacent parts of the stem, said stem having an insulated attaching device for connecting it with a wire or cable, substantially as described.

In testimony whereof I affix my signature in 120 presence of two witnesses.

HENRY HERBERT LUSCOMB.
